(57) **CLAIM**

The ornamental design for a liquid nitrogen cryotherapy device, as shown and described.

DESCRIPTION

FIG. 1 is a front, left, and bottom perspective view of a liquid nitrogen cryotherapy device, showing the new design; FIG. 2 is a rear, right, and top perspective view thereof; FIG. 3 is a front view thereof;

FIG. 4 is a rear view thereof;

FIG. 5 is a left-side view thereof;

FIG. 6 is a right-side view thereof;

FIG. 7 is an enlarged top view thereof; and,

FIG. 8 is an enlarged bottom view thereof.

The broken lines shown in the drawings are included for the purpose of illustrating portions of the liquid nitrogen cryotherapy device that form no part of the claimed design.
